UNITED STATES PATENT OFFICE.

HARRY L. WETHERBEE, OF CHICAGO, ILLINOIS, ASSIGNOR TO FREYN ENGINEERING COMPANY, OF CHICAGO, ILLINOIS, A CORPORATION OF MAINE.

DISTRIBUTOR FOR BLAST FURNACES.

Application filed June 27, 1927. Serial No. 201,952.

The present invention relates to distributors for blast furnaces.

In the charging of blast furnaces it is a problem to distribute the material uniformly throughout the periphery of the furnace.

An object of the present invention is to provide a relatively simple mechanism whereby an improved distribution will be had in a blast furnace.

10 The further object is to provide distributing means for a blast furnace which is adaptable to furnaces as at present designed and which presents very little likelihood of getting out of order.

15 Referring to the drawings:

Fig. 1 is a view in longitudinal section of one embodiment of the present invention.

Fig. 2 is a top plan view on a reduced scale of the structure shown in Fig. 1.

20 Fig. 3 is a longitudinal section view taken along the plane indicated by the arrow 3—3 of Fig. 1.

Fig. 4 is a view similar to Fig. 2, but showing a slight modification.

25 Numeral 10 indicates the upper portion of a blast furnace, which portion is provided with the large charging bell 11 and the small charging bell 12. Said bells 11 and 12 do not depart from present practice, and the 30 means for operating said bells need not be described herein.

Disposed above the small bell 12 is the cylindrical portion 13, which, with the small bell 12, is termed herein, the small bell hopper. Said cylindrical portion 13 has communicating therewith the revolving distributor 14, which distributor, as shown in Figures 2 and 4 is circular in plan view.

35 Disposed above the distributor 14 is the hopper 15, the upper portion of which may be elongated as shown in Figures 2 and 4 for the accommodation of a pair of skips 16—16, one of which is indicated in full lines in Fig. 1, and the other of which is indicated in dotted lines in said figure. In accordance with the common practice, said skips will dump alternately into the hopper 15. Said hopper 15 is provided with the sloping bottom walls 17 for directing material to the 40 revolving distributor 14.

As shown in Figures 1 and 3, the distributor 14 is of conical formation and is provided on its inner side with vanes 18—18.

45 Secured to the outer side of distributor 14 is the gear member 19, which may have

bearing engagement with a casting 20, supported at the upper extremity of the cylindrical member 13. Said gear member 19 may be driven by the pinion 21, which pinion is driven by the motor 22.

50 According to the embodiment of the present invention shown in Figures 1 and 2, the distributor 14 has a bottom aperture of varying diameter, whereby material deposited upon said distributor 14 will be deposited 65 at varying distance from axis of the furnace 10 as the distributor revolves.

55 In accordance with the embodiment of the present invention, shown in Fig. 4, the bottom aperture of distributor 14 is round. The 70 shape of the bottom aperture will be chosen according to the nature of the materials to be handled.

60 In explanation of the present invention it may be pointed out that when material is discharged from a skip, the fine particles tend to segregate themselves from the larger particles on their way to the small bell. The fine particles drop into the near side of the small bell hopper and the coarse material 75 shoots over, filling the far side. Since most furnaces are filled from one side with one or two skips—the result in a non-revolving small bell hopper is to fill up one side of the furnace with dense material (fine particles), 80 while the coarse material covers the rest of the area. This results in channeling, causing rapid wear of the lining and tending toward uneven smelting action. Where the small bell hopper is caused to revolve with a step 90 by step movement before successive dumpings of the bell, there are fixed places where the fine particles will be dumped, giving them a spiral formation throughout the furnace 95 charge.

According to the present invention, however, the fine particles are distributed all around the small bell 12, giving an even distribution around the furnace. By reason of the structure shown in Fig. 2 in which the 100 bottom aperture of the distributor 14 has a cam shaped outline, the distribution of fine particles is rendered relatively uniform from the axis of the small bell to the periphery thereof.

105 It will be clear that the distributor may be revolved by means of the motor 22, while material is being dumped from either of the skips 16. Said motor may be started automatically by means operating in conjunction 110

with the skip mechanism so as to begin motion before a skip begins to discharge and may be stopped automatically when the skip has discharged.

5 Though certain preferred embodiments of the present invention have been described in detail, many modifications will occur to those skilled in the art. It is intended to cover all such modifications that fall within 10 the scope of the appended claims.

What is claimed is:

1. In a blast furnace in combination a revolving distributor having the shape of a

truncated cone, the discharge aperture of which is cam shaped in plan. 15

2. In a blast furnace in combination a revolving distributor having the shape of a truncated cone, the discharge aperture of which is cam shaped in plan, said distributor being provided on its inner side with vanes 20 for causing material deposited on said distributor to revolve with said distributor.

Signed at Chicago, Illinois, this 24th day of June, 1927.

HARRY L. WETHERBEE.
